UNITED STATES PATENT OFFICE.

HOMER HULL, OF DETROIT, MICHIGAN, ASSIGNOR TO AMERICAN BLOWER COMPANY, OF DETROIT, MICHIGAN, A CORPORATION OF MICHIGAN.

LUBRICATING PUMP FOR ENGINES.

Application filed March 13, 1919. Serial No. 282,446.

To all whom it may concern:

Be it known that I, HOMER HULL, citizen of the United States, residing at Detroit, in the county of Wayne and State of Michigan, have invented certain new and useful Improvements in Lubricating Pumps for Engines, of which the following is a specification, reference being had therein to the accompanying drawing.

10 This invention relates to pumps, and while susceptible of different uses, it is more particularly designed for automatic lubrication of engines.

15 Considerable difficulty has heretofore been experienced through defective lubrication of engines, more particularly the small, high speed, vertical type of engines, and it is one of the primary objects of the present invention to generally improve upon lubricating

20 pumps, as at present constructed, for the purpose of adequately and properly lubricating the parts of engines of this particular type.

Many of the lubricating pumps at present largely in use have proven highly satisfactory except when the engine was operating at low speeds, say below fifty revolutions per minute, and when the engine has slowed down, to say as low as ten or twelve revolutions per minute, as is often the case with engines used by automatic stoker manufacturers for engines, for driving blowers for forced draft, it has been ascertained that very little, if any, oil would be pumped, at this time, and it is to overcome this objectionable characteristic and to increase the efficiency and usefulness of the pumps of the character under consideration, that the present invention was developed.

40 Therefore, it may be said to be the purpose and object of the invention to provide a lubricating pump, simple in design and construction, inexpensive to produce, strong and durable, and highly efficient and satisfactory in use for the thorough and continuous lubrication of the engine parts, whether the engine is operating at a high speed, or at a speed even as low as say ten or less revolutions per minute.

45 It is a further object of the invention to provide a lubricating pump unit complete, having the above characteristics whereby the pump may be readily installed, or removed at will, the design and construction being

such as to permit ready assembly on engines of different types.

In carrying out the invention, it is proposed to provide an oscillating oil displacement means operatively associated with the engine and adapted to, in its back and forth movement, continuously feed the oil through a suitable conduit or conduits to the various working parts of the engine to be lubricated.

Further improvements, and many novel details in the construction and arrangement of parts will be appreciated by those skilled in the art from the description to follow, which, for a clear understanding of the invention is to be considered in connection with the accompanying drawings forming a part hereof, and wherein is disclosed, for the purpose of illustration, a convenient and satisfactory embodiment of the invention.

In the drawings,

Figure 1 is a front elevation of the pump, parts being broken away;

Figure 2 is a vertical section of the pump casing and associated parts;

Figures 3 and 4 are sectional views, substantially on the lines 3—3 and 4—4, respectively of Figure 2;

Figure 5 is a detail enlarged of the connection between the engine shaft drive member and actuating means for the pump.

With more particular reference to the drawings, wherein like reference numerals refer to corresponding parts throughout the several views, 1 is an engine shaft or the like, having mounted thereon for rotatable movement therewith, a disc 2, with a peripheral worm cam groove 3. 4 is a vertically disposed pump shaft having secured to the upper end thereof for relative rotatable adjustment as by means of a securing pin 5, an oscillator 6, having a pin or lug 7 tapered to correspond with the tapered wall surrounding the cam groove 3 whereby to engage with the latter while at the same time adapted for free movement along the groove.

A cylindrical pump body 8 is provided, the same conveniently having an integral bottom wall 9, and a removable cap or cover 10, the latter being secured in place as by cap screws 11, whereby to permit of access into the interior oil receiving chamber 12 and parts therein as occasion demands. The cap or cover part 10 conveniently has projecting upwardly therefrom a tubular extension,

which preferably is integral with the cover part as indicated at 13, adapted to loosely surround the pump shaft 4 and having at the upper end thereof an offset bracket part 5 or supporting member 14 adapted to be secured at any convenient point to a fixed part of the engine body whereby to support and maintain the pump in position. It is obvious of course that the supporting connection between the bracket 14 and the wall to which the same is attached, is such as to permit of assembly and removal of the pump as desired, and in this connection the bracket of course may take various designs and configurations whereby to adapt itself to the particular part of the engine or particular type of engine in connection with which it is desired to employ the pump.

The oil impeller or displacement member 20 proper, conveniently takes the form of a round disc 15, secured to the pump shaft 4 for rotatable movement therewith, the said disc having a close fit with the interior peripheral wall of the body part 1 but 25 adapted to oscillate in the chamber formed by the latter. Likewise the thickness of the impeller disc 15 is such as to substantially fill the space between the top and bottom walls of the body part 8. The impeller 30 disc is provided with a segmental cutout part 16 of about one-quarter of the area thereof, though in this connection the degree of cutout may be varied to suit conditions. Positioned within the cutout part is 35 a suitable segment block 17 of a size considerably less than that of the space 16 formed by the cutout part of the impeller disc whereby to permit of relative oscillating movement between the disc 15 and the block 17. This block 17 projects from a snug fit with the pump shaft 4, to a snug fit with the interior peripheral wall of the body part 8, and from top to bottom of said body part 8, whereby to prevent the passage 40 of oil from one side of the partition formed by said block to the opposite side thereof. The partition block 17 is removably secured in place so as to, when positioned, remain rigid with respect to the body part 8 as by 45 means of a tap bolt or the like 18.

Arranged in the bottom of the body part 8 are a plurality of oil inlet ports 19 and 20 respectively, there being one at each side of the partition block 17, and the latter conveniently having cutout parts 21 and 22 respectively, arranged adjacent to said ports. These oil inlet ports 19 and 20 are valve controlled, conveniently by ball valves 23 and 24, loosely positioned within an enlarged chamber 23^a and 24^a of the ports 19 and 20 respectively. The said valves when seated are adapted to entirely close the said ports 19 and 20, and when removed from the restricted portion of said ports the oil 65 has a free passage from the oil supply

through said ports into the chamber formed by the cutout part 16 of the disc 15 and surrounding wall of the body part 8.

The removable cover or cap 10 is likewise provided with ports 25 and 26 respectively, the said ports being in communication with the oil chamber formed by the cutout parts 16 of the disc 15 and surrounding wall of the body part 1 whereby to constitute exhaust ports or outlets from said chamber. The exhaust ports just described, are conveniently formed in removable plugs 25^a and 26^a, respectively, threaded to suitable threaded apertures formed in the cover port or cap 10.

The ports 25 and 26 are provided with enlarged parts 27 and 28 respectively for the reception of ball valves 29 and 30 respectively, which, when seated, normally close the exhaust ports 25 and 26, but which when elevated permit the oil to readily pass through said ports into an oil chamber 31 formed in the cap portion 10 above the plugs 25^a-26^a.

A cylindrical wire screen 32 is secured to the body part 8, being conveniently fitted to the reduced base portion thereof and secured thereto as by means of a removable retaining ring 34 of any desired construction as clearly indicated at 34. The screen is conveniently formed with a screen bottom 35 adapted to prevent dirt and the like from finding its way into the pump parts. The oil discharge chamber 31 has an outlet communicating with an oil distributing pipe or conduit 36 conveniently projecting laterally and thence upwardly for connection in any suitable manner with the parts of the engine to be lubricated, any suitable distributing mechanism in operative association with the conduit 36, not necessary to illustrate or describe, being employed in this connection. The construction and operation may be reviewed as follows:

While the device is described as particularly useful in the feeding of oil, it is to be borne in mind that it is within the contemplation of the invention to utilize the same in connection with the feed of water, gasoline or the like, in which connections the same will be found quite serviceable, and satisfactory in use. The pump being practically all assembled before installation, the same may be installed on any of the approved types of engine, particularly the vertical type, without any material changes in the construction of the latter. Since the vertically disposed tubular extension 13 is, in the preferred embodiment of the invention, formed integral with the cover part or cap 10, this dispenses with any intermediate connecting means thereby making the parts oil tight and whereby to prevent any binding of the shaft with regard to the surrounding wall of the bearing 13 in the relative rotatable movement of the shaft.

Should it become necessary to cleanse the strainer, it is but necessary to remove the detachable retaining ring 34 whereupon ready access to the interior of the strainer or screen 5 or access to the ports 19 and 20 and associated parts may be obtained.

By reason of the adjustable connection between the oscillator 6 and rotatable shaft 4, the impeller or oil displacement member 15 10 may be properly centered with respect to the block or partition 17 positioned in the segmental cutout part of the impeller 15.

The pump is a double acting one, and needs no packing, stuffing boxes, glands, or 15 piston rings to contend with.

In operation the pump is mounted, through the medium of the bracket support 14, upon the frame-work of the engine, whereby to position the lower or screen end 20 thereof within the oil chamber constituting the means of supply, and so soon as the engine is started, the engine shaft 1 imparts continuous rotatable movement to the connected disc 2 when the oscillator 6 through 25 the medium of its connection formed by the projecting pin or lug 7 with a cam groove 3, will have imparted thereto, and will in turn impart to the shaft 4, a back and forth or oscillating movement. As the impeller or 30 oil displacement disc rotates or oscillates back and forth, it squeezes or forces the oil out of the intervening space between the impeller and stationary block 17, the oil finding exit in each movement of the impeller disc 15 into one or the other of the oil outlets 25-26 from whence it flows through the oil chamber 31 and is elevated through the discharge conduit 36. The oil discharge is 35 of course continuous because of the provision for a discharge as the impeller disc 15 moves either forward or backward. Likewise, in each forward and backward movement of the impeller disc 15, oil is drawn into the chamber formed by the cutout part 40 of the disc 16 and stationary block 17 upon one side or the other of said block through the valve controlled ports 19-20. As the impeller disc is moved in one direction, the oil to one side of the stationary block is 45 forced out of the exhaust port 25, the ball valve 29 being at this time elevated, whereas the inlet valve 23 is maintained seated. On the other hand as the impeller is moved in 50 an opposite direction, the oil on the opposite side of the stationary block 17 is forced out of the exhaust port 26, the valve 30 at this time being elevated, whereas the inlet valve 24 is seated.

It has been ascertained in practice that 55 the pump operates to continuously feed the oil in an efficient manner, whether the engine be speeded up or slowed down to say below ten revolutions per minute, and in this particular has many advantages over

prior similar constructions heretofore in 65 use, and with which I am familiar.

What I claim is:

1. In a pump of the character described, the combination of a stationary body part, comprising substantially flat end walls and a cylindrical side wall, a shaft projecting through one of the end walls, an impeller member within the chamber formed by the body part, said impeller member being solid and mounted on said shaft so as to substantially fill the space between the flat end walls and curved to conform to the curvature of the cylindrical wall, the body part having inlet and exhaust ports in the flat end walls thereof, said impeller member having a segmental cut-out part projecting inwardly from the periphery thereof, a stationary partition mounted on the body part and within the space formed by said cut-out part of the impeller member, and mechanical means for continuously imparting oscillating movement to the shaft about its longitudinal axis whereby to oscillate the impeller member. 80

2. In a pump of the character described, the combination of a vertically disposed stationary body part having a cylindrical oil chamber, a solid disk-shaped horizontally disposed impeller in the chamber, said impeller being of a thickness to closely fit the top and bottom walls of the chamber, means for oscillating the impeller about a vertical axis, and means whereby the oil is continuously drawn into and discharged from the body part in the oscillating movement of the impeller. 95

3. In a pump of the character described, the combination of a vertically disposed cylindrical stationary casing forming a chamber, the bottom and top walls of which are provided with inlets and outlets, a vertically disposed shaft projecting through one end of the casing, a segmental partition positioned within the casing and projecting from the wall of the casing to the shaft, a horizontally disposed solid impeller disk fixed on the shaft and having a segmental cut-out part of a width in excess of that of the segmental partition, and means operatively associated with the shaft for imparting oscillating movement to the impeller disk. 105

4. In a pump of the character described, the combination of a vertically disposed stationary cylindrical body part having substantially flat top and bottom walls with inlet and exhaust ports therein, a horizontally disposed solid impeller disk positioned in the body part and closely fitting the walls of the same and having a segmental cut-out part projecting from its periphery inwardly, a shaft adapted to move about a vertical axis, projecting through the body part and connected to said impeller disk, a partition 110

in the body part in the space formed by the cut-out part of the impeller disk and slightly spaced at its sides therefrom, means for oscillating the shaft, and movable means 5 operatively connected directly with said shaft for automatically imparting continuous oscillating movement thereto.

5. In a pump of the character described, the combination of a vertically disposed stationary cylindrical body part, having closed top and bottom walls, an oscillating impeller segment in the body part closely fitting the same to prevent movement of the oil around the impeller leaving an oil space located between the ends of the impeller, a partition 10 in the body part in said space, means for imparting continuous oscillating movement to the impeller about a vertical axis, the bottom wall of the body part having inlets to said space, one at each side of said partition; and the top wall having exhaust ports in communication with said space, one at each side of the partition, the top wall also having in communication therewith a discharge conduit to deliver the discharged oil to the parts to be lubricated.

6. In a pump of the character described, the combination of a vertically disposed stationary cylindrical body part, having closed top and bottom walls, an oscillating horizontally disposed impeller segment in the body part closely fitting the same to prevent passage of the oil around the impeller leaving an oil space located between the ends of the impeller, a partition in the body part in said space, power-driven means for imparting continuous oscillating movement to the impeller about a vertical axis, the bottom wall of the body part having inlets to said space, one at each side of said partition; and the top wall having exhaust ports in communication with said space, one at each side of the partition, the top wall also having in communication therewith a discharge conduit to deliver the discharged oil to the parts to be lubricated, automatically operable valves for each of said ports, and the top wall of the body part being removable to permit access to the interior of the body part and parts therein.

7. In a pump of the character described, the combination of a vertically disposed stationary cylindrical body part, having closed top and bottom walls, an oscillating horizontally disposed impeller segment in the body part closely fitting the same to prevent passage of the oil around the impeller leaving an oil space located between the ends of the impeller, a partition in the body part in said space, power-driven means for continuously imparting oscillating movement to the impeller about a vertical axis, the bottom wall of the body part having inlets to said space, one at each side of the partition,

the top wall also having in communication therewith a discharge conduit to deliver the discharged oil to the parts to be lubricated, automatically operable valves for each of said ports, and the top wall of the body part being removable to permit access to the interior of the body part and parts therein, and a screen underlying the body part whereby to protect the inlet ports.

8. In a pump of the character described, the combination of a vertically disposed cylindrical stationary casing forming a chamber, the bottom and top walls of which are provided with valve-controlled inlets and outlets, a vertically-disposed shaft projecting through the top wall of the casing, a segmental partition positioned within the casing and curved to conform to the wall of the casing and the periphery of the shaft, a horizontally disposed solid impeller disc fixed on the shaft and having a segmental cut-out part of a width in excess of that of the segmental partition, and means operatively associated with the shaft for imparting oscillating movement to the impeller disc, which said disc is of a thickness to substantially fill the space in the casing between the top and bottom walls thereof.

9. In a pump of the character described, the combination of a rotatable cam member mounted on a horizontal axis and having a peripheral cam groove, a vertically disposed shaft having connected directly thereto a cam groove engaging member, whereby said shaft will receive continuous oscillating movement under the action of the cam groove, a stationary vertically disposed casing having closed top and bottom walls, the said shaft projecting through the top wall of the casing, a horizontally disposed impeller disc secured to said shaft of a thickness to substantially fill the space between the top and bottom walls of the casing, the said disc having a segmental cut-out part in its periphery, a partition fixed to the side wall of the casing of a width less than the width of the segmental cut-out part of the disc, the bottom wall of the casing having inlet ports one at each side of said partition, and the top wall of the casing having exhaust ports, and all of said ports being valve-controlled.

10. In a pump apparatus of the character described, the combination of a vertically disposed casing having closed top and bottom walls, a vertically disposed oscillating shaft projecting through the top wall of the casing, a segmental partition secured to the side wall of the casing arranged therewithin and extending from top to bottom of the casing and from the shaft to the side wall of the casing, a horizontally disposed solid disc mounted on the shaft and of a thickness to substantially fill the space be-

tween the top and bottom walls of the casing, said disc having a segmental cut-out of a width greater than that of the partition, the bottom wall of the casing having valve-
5 controlled inlet ports, one at each side of the partition, removable plugs in the top wall of the partition, said plugs having an outlet

port therein, and valves in said outlet ports. In testimony whereof I hereunto affix my signature in the presence of two witnesses.

HOMER HULL.
